UNITED STATES PATENT OFFICE.

JOHN DUCHOW, OF MONTREAL, QUEBEC, CANADA.

ACCOUNTING-BOOK.

1,283,700.

Specification of Letters Patent.

Patented Nov. 5, 1918.

Application filed December 29, 1917. Serial No. 209,458.

To all whom it may concern:

Be it known that I, JOHN DUCHOW, a subject of the King of Great Britain, and resident of 20 Fairmount avenue west, in the city and district of Montreal, in the Province of Quebec, in the Dominion of Canada, have invented certain new and useful Improvements in Accounting-Books, of which the following is a specification.

10 The invention relates to improvements in accounting books as described in the present specification and illustrated in the accompanying drawings that form part of the same.

15 The invention consists essentially of the novel means employed for marking certain places in the book for attention at definite times.

20 The objects of the invention are to facilitate the management of many accounts in a book, where attention to the same is required at varying dates according to the terms and conditions of the several accounts, to eliminate the losses and inconveniences 25 incident to the lapses of memory of the clerk in regard to the obligations of customers and others, to devise a new system of noting various accounts operable by comparatively inexperienced clerks and always 30 at hand to the superior, and generally to provide a new form of book simple to operate and cheap to produce.

35 In the drawings, Figure 1 is a view of a book showing the cover broken away and disclosing the calendar days of a long month on the inner side of the back cover.

Fig. 2 is a plan view of the sheet.

Fig. 3 is a detail of a marker.

40 Fig. 4 is a plan view of a marker showing the gummed ends.

Fig. 5 is a view showing the markers in a plurality of colors.

Like numerals of reference indicate corresponding parts in each figure.

45 Referring to the drawings, the sheet 51 is perforated along an edge preferably the top edge to form a row of openings 52 comparatively close together and here shown as rectangular in shape, though they may 50 be of any shape or size and in any number, but they will likely be as shown one for each day of a long calendar month and three or four over.

The numerals running from 1 to 31 consecutively are printed over the openings 52 starting from left to right, or from right to

left as found convenient or in any order to suit the conditions of use.

The same set of numerals 1 to 31 are mounted, printed, embossed or otherwise reproduced on the inside of the back cover 53 in alignment with the numerals on the sheet 52. Therefore when a page of the book is marked by passing the marker 54 through one of the openings 52 and sticking the ends together therebeyond by means of the gummed ends 55, the said marker points to the date on the cover row of numerals, as for example, if it is desirable to look up an account on the 7th day of the month, one 70 of the markers 54, formed of a short strip of paper or other suitable material, is inserted through the opening marked 7 and stuck together beyond the edge of the sheet. The protruding marker will then point to 75 the numeral 7 on the inside of the back cover and the accountant will know that there is something to be done to that account on that day.

80 The markers are preferably made of different colors to indicate certain facts about the accounts marked, thereby enabling the merchant to see at a glance without even opening the book, how many accounts are going bad or getting into a dangerous state. 85

Many changes may be made in this invention as to its construction and uses without departing from the spirit of the invention, so long as they are within the scope 90 of the claims for novelty following.

95 It may be pointed out in regard to the colored markers that they may be varied to such an extent as to denote accounts previous and bad, as mentioned hereinbefore, accounts wherein there are prospects for future sale, instalments due, accounts collectable without the aid of a diary, in fact in many respects eliminate the use of a diary.

100 What I claim is:—

1. In a book, a plurality of leaves, each of said leaves having a row of holes adjacent to an edge and a designation for the majority of holes, a corresponding indicator having the same designations and markers shaped to fit in said holes and project beyond the edge of the leaf. 105

2. In a book, a plurality of leaves, each of said leaves having a row of holes adjacent to an edge, one for each day of the month and numbered 1 to 31 and as many more as required, a mounted sheet contain-

ing numerals 1 to 31 in register with the aforesaid numbers and on the inside of the back cover and a plurality of markers suitably colored and having gummed ends and shaped to fit in said holes and extend beyond the edge of the leaves.

3. In an article of the class described, a plurality of grouped leaves, each having a row of holes adjacent to an edge, an index

row associated with said leaves, and a plurality of markers fitting in said holes and projecting beyond the edge of the leaves and made in a variety of colors denoting respectively good, bad, precarious and other accounts needing reminders.

Signed at the city of Montreal, Quebec, Canada, this 15th day of December, 1917.

JOHN DUCHOW
